(57) **CLAIM**

The ornamental design for a deck hatch, as shown and described.

DESCRIPTION

FIG. 1 is a top perspective view of a closed position of the deck hatch showing my new design;
FIG. 2 is a top plan view thereof;
FIG. 3 is a bottom view thereof;
FIG. 4 is a right side view thereof;
FIG. 5 is a left side view thereof;
FIG. 6 is a rear side view thereof;
FIG. 7 is a front view thereof; and,
FIG. 8 is an enlarged partial top front perspective view thereof.

The dash-dot broken lines represent the boundaries of the enlarged partial view of FIG. 8. All other broken lines represent portions of the deck hatch that form no part of the claimed design. None of the broken lines form a part of the claim.
